Specification for Design.

Patented July 29, 1913.

Application filed February 25, 1913. Serial No. 750,700. Term of patent $3\frac{1}{2}$ years.

To all whom it may concern:

Be it known that I, AXEL J. NELSON, a citizen of the United States, and a resident of the city of Chicago, county of Cook, and State of Illinois, have invented a new, original, and ornamental Design for Tie-Clasps, of which the following is a specification, reference being had to the accompanying drawing, forming a part thereof.

In the drawing Figure 1 is a front view of a tie clasp, showing my design, and Fig. 2 is a top plan view thereof.

I claim:

The ornamental design for a tie clasp, as shown.

In testimony whereof I have signed my name to this specification in the presence of two subscribing witnesses.

AXEL J. NELSON.
